UNITED STATES PATENT OFFICE.

FREDERICK HACHMANN, OF ST. LOUIS, MISSOURI, ASSIGNOR TO WILLIAM H. GREGG,
OF ST. LOUIS, MISSOURI.

MANIFOLD SALES BOOK AND COVER.

Application filed April 23, 1921. Serial No. 463,353.

To all whom it may concern:

Be it known that J. FREDERICK HACHMANN, a citizen of the United States, and resident of the city of St. Louis, and State 5 of Missouri, have invented certain new and useful Improvements in Manifold Sales Books and Covers, of which the following is a specification, containing a full, clear, and exact description, reference being had 10 to the accompanying drawings, forming a part hereof.

My invention relates to improvements in manifold sales books and covers therefor, and has for its primary object a manifold 15 sales book in which the original and duplicate and a tissue copy are made simultaneously, the whole being mounted on a back of relatively stiff material. The original and duplicate capable of being removed 20 therefrom, while the tissues remain permanently attached to the back.

A further object is to construct a cover for a manifold sales book as above described, which cover holds the sales book 25 on both ends and which is provided with an extra leaf to which the sales book is attached, the tissue sheets being adapted to be folded beneath the extra leaf after being filled out, and one of the covers being provided with a pocket for holding a total 30 sales ticket.

In the drawings,

- Fig. 1 is a plan view of my improved sales book.
35 Fig. 2 an enlarged longitudinal section of the same with some of the original and duplicate tickets removed and showing the manner of folding the tissues backward and under the sales book.
40 Fig. 3 is a side elevation of my improved sales book and cover.
Fig. 4 a top plan view with the top cover removed.
Fig. 5 a bottom plan view.
45 Fig. 6 an end view with the sales book removed.
Fig. 7 a top plan view of the top cover showing the total sales ticket in position.
50 Fig. 8 a sectional view taken on the line 8-8 of Fig. 7.

In the construction of my device I employ a manifold sales book having a back 9. This back is formed of relatively stiff material such as cardboard and the like. 55 Adjacent one edge of the back 9 are se-

cured the tissue sheets 10. These sheets are secured by means of staples 11 and edging 12 through which the staples pass. This edging is for the purpose of preventing the tissue sheets from tearing loose and being 60 pulled out of the staples. The tissue sheets are also provided with openings 13 which are near the end where the staples 11 pass through. These openings are for the purpose of permitting the passage of staples 65 14 which secure the originals 15 and duplicates 16 to the back 9.

Secured to the opposite end of the back 9 are carbon sheets 17 which are held in position by means of staples 18. These 70 carbon sheets are spaced apart by means of fillers 19. The purpose of these fillers is to reduce the length of the carbon sheet, for the reason that as the sales book is used up, the carbon sheet is gradually lowered 75 and this would in time necessitate the trimming of the one end of the carbon, so that it would not butt against the staples 14 while the sales book is being used. These carbon sheets are provided with a cutaway 80 portion 20, the purpose of which is to permit the insertion of the finger so that the sheets may be pushed from underneath the carbon without the necessity of fingering the carbon, which is doubled faced would not 85 only soil the fingers but also cause smears on the sales tickets.

After the book has been assembled, it is secured within the cover which consists of a top cover 21 and back cover 22 and an 90 intermediate leaf 23. The top cover is provided with eyelets 24 through which the hinge wire 25 passes. The top cover is also provided with beaded edges 26 for stiffening purposes and with the folded portion 27, this folded portion together with the beads 26 clamping the plate 28 securely to the back. This plate has its outer edge slightly upturned, (see Fig. 8) so as to form a groove for one end of the total 100 sales ticket 29. The cover is also provided with a bead 30. This bead having an extension 31 which is also upturned to form a groove for the opposite end of the sales ticket 29, and in order to prevent the cover 105 from scratching the furniture its outer face is provided with the rectangular bead 32. Formed integral with the cover 22 and bent at right angles is a back 33, which is provided along its upper edge with loops 34, 110

through which the hinge wire 25 passes, thus securely holding the two covers together. The opposite ends of the cover 22 is provided with loops 35, through which 5 the hinge wire 36 passes. The intermediate cover 23 is provided with loops 37, through which the hinge wire 36 passes, thus securing the covers 22 and 23 hinged together. Secured to the hinge wire 36 is a 10 spring clamp 38 which is provided with loops 39. This spring clamp as well as the intermediate cover 23 are provided with teeth 38 which are adapted to securely grip the carbon end of the sales book. Surrounding the hinge wire 26 are coil springs 40 which exert pressure against the clamp 38 and hold it in contact with the sales book. The opposite end of the intermediate leaf 15 is provided with a right angular projection 41. The upper end of which is again bent at right angles as indicated at 42 so as to form a slide into which one end of the sales book can be slipped. This secures the other end of the sales book. The portion 20 42 is provided with projecting ends 43 which project beyond the edges of the sales book. This is for the purpose of raising the leaf or cover 23, so that the used tissue sheets 10 can be folded thereunder.

30 The operation of my device is as follows: After the sales slip has been filled out, the original is torn off, this original coming away clean from the staples, so that no part thereof will remain. The tissue sheet is then 35 raised and by reason of the openings 13 will swing over the staples 14, the tissue sheet is then inserted between the cover 22 and leaf 23. The finger is then inserted in the opening 20 formed in the carbon sheets and the duplicate 16 pushed out from under the carbon where it is torn from the staples 14 coming 40 away clean the same as the original. The finger is then again inserted in the opening 20 and the original and tissue sheets pushed forward and removed from underneath the carbon and allowed to rest thereon. This 45 places the book in position for the next sale, after which the foregoing operation is completed. I may also, if desired, perforate the 50 originals and duplicates along a line through which the staples 14 are inserted. This will be an additional assurance that the original and duplicate sheets will come away clean from the staples. After all the originals and 55 duplicates have been used up, the carbon sheets are removed from the back 16 and

the tissue sheets which are bound to the back, sent to the proper officer for checking up with the duplicates which have been retained by the cashier. In this manner 60 there is no possibility of any of the tissue sheets becoming lost or deranged, and they will always follow in the sequence they were made out.

Having fully described my invention, what I claim is:

1. A manifold sales book comprising in combination with a metal book cover, a back, a plurality of tissue sheets having openings formed therein secured to said back, a plurality of original and duplicate sales tickets located between said tissue sheets, staples for securing said sales tickets to the back, said staples passing through the openings formed in the tissue sheets, and a plurality of carbon sheets removably located between certain of the tissue and duplicate sales tickets, means for securing said carbon sheets to the back, and means for securing the sales book within the cover. 75

2. A manifold sales book comprising in combination with a hinged metal cover, a back of relatively stiff material, a plurality of tissue sheets having openings formed therein secured to said back along one of its edges, a plurality of original and duplicate sales tickets located between said tissue sheets, staples for securing said sales tickets to said back, said staples passing through the openings formed in the tissue sheets, a plurality of carbon sheets having a cutaway portion on one of their side edges secured to said back and adapted to be inserted between the tissue and duplicate tickets, said opening allowing the removal of tissue and original sheets from beneath the carbon, and means for securing the sales book within the cover. 90

3. A manifold sales book and cover therefor, comprising a sales book having original and duplicate sales tickets, and a plurality of tissue sheets, a top and back cover hinged together, an intermediate leaf hinged to said back cover, means carried by said leaf for securing to 105 ends of the sales book thereto, and a groove formed in the top cover and a total sales ticket located in said groove.

In testimony whereof, I have signed my name to this specification.

FREDERICK HACHMANN.
